UNITED STATES PATENT OFFICE.

ARCHIBALD THORPE CROSHER, OF TE AROHA, NEW ZEALAND.

METHOD OF CONNECTING ELECTRIC WIRES TO LAMP-HOLDERS, PLUGS, AND THE LIKE.

1,060,822.

Specification of Letters Patent.

Patented May 6, 1913.

Application filed January 18, 1911. Serial No. 603,375.

To all whom it may concern:

Be it known that I, ARCHIBALD THORPE CROSHER, a citizen of the Dominion of New Zealand, and residing at Te Aroha, in the 5 Provincial District of Auckland, in the Dominion of New Zealand, have invented certain new and useful Improvements in Methods of Connecting Electric Wires to Lamp-Holders, Plugs, and the Like, of which the 10 following is a specification.

The invention relates principally to lamp holders used in connection with incandescent electric light bulbs.

Hitherto in the method generally employed 15 the wires are led through a wooden tapering plug in two parts and the ends of the wires are gripped in screw terminals. This arrangement has the disadvantage that there is a direct strain or grip upon the insulation 20 and there is considerable inconvenience in preparing the plug for the reception of the wires, and in fixing them in position.

According to my invention, a block of insulating material has a central hole through 25 which the wires are passed. Each wire is then independently carried upward in a recess formed for its reception in the block, and is then turned over and downward through a hole to the terminal of the lamp holder, 30 within which it is fixed by the usual binding screw. The block is carried within a dome secured to the lamp socket by a ring nut in the usual way. The block can be made of the same diameter as the usual porcelain terminal 35 holder.

By my invention even when the wires are released from the terminal grips it is practically impossible to pull the wire out of the plug by a direct pull, better insulation is effected than hitherto, and the lamp holder is held with greater security.

My invention is illustrated in the drawing wherein:—Figure 1, is a front elevation of the lamp holder, Fig. 2, a similar view with the parts displayed, Fig. 3, a plan of the insulating block with the dome removed, Fig. 4, an inverted plan of the insulating block, Fig. 5, a sectional plan on A—A, Fig. 2, Figs. 6 to 9 inclusive, illustrate a modification and therein Fig. 6, is an elevation one half in central section of a lamp holder, Fig. 7, a perspective elevation of an insulating block in two parts, Fig. 8, an inverted perspective plan of the upper part of the block, Fig. 9, a perspective elevation, and

Fig. 10, an inverted plan of the lower part of the block.

Referring first to Figs. 1 to 5 inclusive, the insulating block 1 has a central hole 2 through which pass the wires 3 and 4. Wire 60 3 is carried upward in a curved recess 5 thence downwardly through a hole 6 and its end connected to terminal 7 by the usual binding screw 8. Wire 4 is carried in a similar way in the curved recess 9 thence 65 downwardly through hole 10 and its end secured to terminal 11. A boss 12 projecting from the block fits a hole in the covering dome 12^a which is secured to the lamp socket 13 by the usual ring nut 14. Both wires are 70 covered with insulating material except where electrical connection is made with the terminals.

Referring now to Figs. 6 to 10 inclusive, the dome 15 and lamp socket 16 are integrally formed, the socket being screw threaded at 17 to receive the nut which supports the shade. The insulating block is in two parts 18 and 19 and the electric wires 20 and 21, are carried through a central hole 22 common to both parts. The wire 20 is carried diagonally upward in the curved recess 23 and from thence down through a hole 24 in the upper part of the block and its end connected by binding screw 25 to the plunger 85 terminal 26 which projects through the lower part of the block and at its upper end fits a recess 27 in the lower face of the upper block. Wire 21 is carried in a similar manner in the recess 28 downwardly through the hole 90 29, and its end connected by the binding screw 30 to the plunger terminal 31, which is carried in the two parts of the block in the same manner as plunger terminal 26. Lateral recesses 32 and 33 give access to the 95 binding screws when the two parts of the block are together. The upper part 18 of the block has a projecting boss 36 which projects through a hole in the dome 15. The socket 16 is indented to provide an internal 100 projection which engages in a groove 34 in the two parts of the insulating block to hold it with the plunger terminals in correct position relatively to the "bayonet" slots 35 by which the lamp is connected.

What I do claim and desire to secure by Letters Patent of the United States is:—

1. In a lamp holder, an insulating block having a central hole adapted to receive both wires of an electrical circuit and two holes, 110

- one for each of said wires independently, and diagonal recesses in the periphery of the block, said recesses severally communicating with the bottom of the central hole 5 and with the top of one of the other holes, substantially as and for the purpose herein specified and illustrated.
2. In a lamp holder an insulating block in two parts, a dome and socket receiving 10 said block, a central hole corresponding in the two parts of the block, curved recesses, one for each wire, and communicating with said central hole, holes one from the top of each of said recesses passing through the upper part of the block, plunger terminals on the lower part of the block and recesses in the face of one of the blocks to receive the binding screws of the terminals and to give 15 access thereto substantially as herein specified and illustrated.
3. In a lamp holder, the combination of an insulating block, comprising two coöperating parts, each part having a corresponding centrally arranged hole to receive both wires 20 of an electrical circuit, two holes in one of said parts, one for each of said wires independently, and lamp terminals on the other part projecting into said holes and to which said wires are adapted to be connected.
4. In a lamp socket, the combination of an insulating block having a centrally arranged opening therethrough and strain relief passages communicating with the centrally arranged opening, one passage for each of said 25 wires independently, and spaced lamp ter-

minals on one face of said insulating block having wire terminals adapted to be electrically connected with the wires extending through said passages.

5. In a pendent electric appliance, the 40 combination of an insulating body comprising two coöperating parts each having a central opening therein arranged to receive both wires of an electrical circuit, other openings in said block and extending through both 45 parts, passageways connecting said central opening with said other openings, lamp terminals seated in said other openings, the circuit wires being adapted to extend into said openings at the opposite ends and be 50 secured to the lamp terminals.

6. In a device of the class described, the combination of an insulating block comprising two separable parts having corresponding central openings therethrough to provide 55 an opening extending through the block to receive both wires of an electrical circuit, an inclosing casing for the block, means on the casing coöperating with the block to prevent the movement of one independent of 60 the other and separated terminal posts within one of said parts adapted to be connected to the circuit wires and constituting lamp contacts at the lower face of the part in which they are mounted. 65

Dated at Auckland, New Zealand.

ARCHIBALD THORPE CROSHER.
